WILLIAM E. A. PIPHER, OF PARKERS LANDING, PENNSYLVANIA, ASSIGNOR OF ONE-
FOURTH TO CHARLES A. SHERWOOD, OF PARKERS LANDING, PENNSYLVANIA.

WELL-DRILLING APPLIANCE.

1,005,301.

Specification of Letters Patent. Patented Oct. 10, 1911.

Application filed December 12, 1908. Serial No. 467,216.

To all whom it may concern:

Be it known that I, WILLIAM E. A. PIPHER, a citizen of the United States, residing at Parkers Landing, in the county of 5 Armstrong and State of Pennsylvania, have invented a new and useful Well-Drilling Appliance, of which the following is a specification.

This invention relates to appliances for 10 supporting tools used for drilling Artesian and similar wells.

It is the primary object of the present invention to provide an improved means for 15 supporting tools for drilling Artesian and similar wells, and to overcome the disadvantages of such supporting means as are now employed, at the same time combining their advantages.

It is a well known fact that a rope is more 20 satisfactory than a wire cable for the purpose of supporting the tools employed in drilling Artesian or other similar wells, owing to the fact that such rope possesses certain resilient properties which act to permit rebound or jar of the drilling tool at 25 each stroke thereof. The disadvantage of such a supporting means however resides in the fact that it is extremely liable to become broken and does not wear as long as does 30 a wire cable. On the other hand, however, a wire cable does not possess the properties of elasticity contained in the hemp or other rope, and there is no rebound of the drilling tool at the termination of each stroke.

It is the object of the present invention 35 therefore to provide means whereby any ordinary well-drilling tool may be supported at the end of a wire cable, and the proper rebound of the tool be had in spite of the 40 employment of the cable, and the invention even goes a step farther by providing for adjustment of the device to the proper degree of tension or resiliency, so that it may be quickly adapted for use in connection 45 with tools of varying weight.

With the above and other objects in view, the invention consists in the construction and arrangement of parts hereinafter described and set forth in the claim, and 50 shown in the accompanying drawings, in which:—

Figure 1 is a longitudinal sectional view through the device embodying the invention: Figs. 2 and 3 are horizontal sectional

views, on the lines 2—2 and 3—3 respectively, of Fig. 1 looking upward in Fig. 3.

In the drawings, the device embodied in the invention is illustrated as comprised in part of a cylindrical barrel 5, which has its upper end contracted to form a shoulder 6, and is interiorly threaded at its lower end, as at 7, to receive a threaded stud 8, formed at the upper end of a coupling member 9, which, in turn, is formed in its lower end with a threaded socket 10, to receive the upper threaded end of a drilling tool (not shown). The barrel 5 is further provided, at its upper end, with a tubular extension 11, the bore 12 of which extends axially of the barrel, and slidably disposed within the barrel and projecting at its upper end into the bore of the tubular extension 11, is a tubular plunger 13, the said plunger being screwed at its lower end into the threaded bore 140 of a cylindrical head 14, which is 75 of substantially the same diameter as the bore of the barrel, and slides therein. It will be seen that the plunger stem 13 is of such length as to project at its upper end into the tubular extension 11 of the barrel 80 when the head 14 of the plunger is at rest against the stud 8 of the coupling element 9.

In order to exert a constant tension against the plunger in the direction of its lower end, a plurality of short helical 85 springs 15 and interposed sleeves 16 are disposed upon the stem 13 of the plunger, the sleeves 16 being arranged one between each pair of the springs, and the uppermost spring bearing at one end against the 90 shoulder 6, and the lowermost spring bearing at its lower end against the plunger head 14. It is preferable that the springs 15 be under a certain degree of compression, even when conditions are normal, under 95 which conditions the head 14 of the plunger will bear against the upper end of the stud 8 of the connection 9; and this degree of compression to which the springs are normally subjected may be varied by removing 100 one or more of the springs, or inserting one or more such springs, it being understood that, in the first instance, less energy will be required to move the plunger in the direction of the upper end of the barrel than 105 in the latter instance. The plunger head 14 is provided, in its under face, with a socket 17, which is intended to receive the knotted

lower end of a wire cable 18, which rests against the lower end of the plunger 13 and supports the device, and through the medium of the device the drilling tools; it 5 being understood that additional compressive force is imposed upon the springs within the barrel 5 by the weight of the drilling tools, and that the degree of such force is proportionate to the weight of the 10 tools.

From the foregoing description it will be understood that while the wire cable 18, in itself, possesses no elasticity, at each stroke of the tool, the upward pull upon the cable 15 18 will serve to place the springs 15 under a higher degree of compression than at any other time, and that these springs, in resuming the original or normal state, will cause a rebound of the drilling tool. It will 20 be understood, further, that while all the advantages accruing from the employment of a wire cable as the tool-supporting means, are obtained, the further advantages which would accrue from the employment of an 25 elastic supporting means, such as a hemp rope, are also secured; and it will further be apparent that, by removing one or more of the springs 15, or inserting one or more such springs, the tensile strength of the 30 device may be varied to adapt the same for employment with heavy or light tools, and to attain the desired rebound of a tool of any weight employed.

It will be observed, from an inspection 35 of Fig. 1 of the drawings, that certain of the springs 15 are of greater length than the others, although their helices are of the same diameter, so that certain of the springs may be said to have a tensile strength 40 greater than certain other of the springs, and, while this arrangement of springs is not absolutely essential to the attainment of the results, yet, the advantage of such an arrangement lies in the fact that a wider range 45 of adjustment may be secured than would be possible should all of the springs be of the same length. In other words, whereas, in the arrangement shown and just described, one of the longer springs might be 50 removed to secure the proper adjustment; should all of the springs be of the same length, it might be found that neither the removal of one nor two of the springs would produce the desired result.

By referring to the drawings it will be 55 noted that the sleeves 16 are of considerable length so as to present extensive bearing surfaces to the inner surface of the barrel 5. As a result, these sleeves will not tilt or cant under the pressure of the springs, said 60 springs bearing upon the sleeves at points removed from the centers thereof. Moreover these sleeves reinforce the tubular plunger 13 and prevent it from buckling or getting out of a straight line during its sudden movement within the barrel. It will be seen that the head 14 fits snugly upon the stud 8 under normal conditions and that the knot at the lower end of the rope is seated within a recess or socket 17. It will be seen, 70 therefore, that when the head 14 is moved downwardly the knot at the lower end of the rope will not strike the stud 8 and cushion the head 14 but will be held practically out of contact with the stud. 75

What is claimed is:—

A well drilling appliance including a cylindrical barrel, a threaded stud closing one end thereof and having a tool receiving socket in its outer end, there being a tubular extension at the other end of the barrel, a tubular plunger mounted to reciprocate within the barrel and extension, a plunger head detachably engaged by one end of said plunger and normally pressing flat upon the inner end of the threaded stud, that face of the head contacting with the stud being formed with a tapered socket, a rope extending through the tubular plunger and having a knotted terminal seated within the 90 socket and above the lower face of the plunger head, a series of helical springs extending around the plunger and within the barrel, the end springs bearing against the plunger head and one end of the barrel respectively, and combined spacing and reinforcing rings fitting slidably on the plunger and within the barrel, said rings being interposed between the springs and constituting bearings for the ends thereof. 95

In testimony that I claim the foregoing as my own, I have hereto affixed my signature in the presence of two witnesses.

WILLIAM E. A. PIPHER.
